CLAIM

The ornamental design for a toaster oven, as shown and described.

DESCRIPTION

FIG. 1 is a perspective view of a toaster oven showing our new design;

FIG. 2 is a front view thereof;

FIG. 3 is a right side view thereof;

FIG. 4 is a top view thereof;

FIG. 5 is a left side view thereof;

FIG. 6 is a rear view thereof; and,

FIG. 7 is a bottom view.

The details shown in broken lines form no part of the claimed design.
